CLAIM

The ornamental design for a toy trackway, as shown and described.

DESCRIPTION

FIG. 1 is a top perspective view of a toy trackway showing our new design;

FIG. 2 is a top plan view thereof;

FIG. 3 is a side elevational view thereof;

FIG. 4 is a cross-sectional view thereof taken along line 4—4 in FIG. 2 shown on an enlarged scale; and

FIG. 5 is a cross-sectional view taken along line 5—5 in FIG. 2.
